WIDE BAND ANTENNA STRUCTURE

Marvel W. Scheldorf, Syracuse, N. Y., assignor
to General Electric Company, a corporation of
New York

Application April 11, 1946, Serial No. 661,214

1 Claim. (Cl. 250—33.53)

1

My invention relates to antennas for operation over a wide band of radio frequencies and it has for its object to provide a new and improved antenna suitable for use for television and other purposes requiring wide band operation.

A general characteristic of antennas having a narrow band of satisfactory operation is one of rapid variation in reactance relative to the resonant resistance. The slope of this reactance may be either positive or negative, the only major difference being that antennas with a negative reactance slope may be compensated more easily by associated terminal transmission line units. I have found that the band width of the usual antenna is limited primarily by the cross-sectional dimension of the radiators employed which dimension, in turn, determines the antenna reactance. Furthermore, a serious limiting factor is the limitation placed upon band width by the terminal end of the radiating structures. In the past, attempts have been made to improve the reactance characteristics of antennas by enlarging the outer ends of the radiator, while the terminal ends were confined to the size of a small transmission line conductor, thus to reduce the reactance to a low value. It is an object of my invention to provide a new and improved wide band antenna in which the radiators thereof are of uniform dimensions throughout their lengths and are so related spatially that they have the effect of a large radiating sheet.

It is another object of my invention to provide new and improved methods and means of coupling radiators in an antenna having a plurality of radiators.

It is a further object of my invention to provide a new and improved wide band antenna having improved impedance characteristics.

It is a still further object of my invention to provide a new and improved wide band antenna in which the radiators thereof are so spaced that their mutual inductance is a minimum.

One of the features of my invention consists in employing spaced radiators which are uniform throughout their lengths and so connected that they are fed in phase to operate effectively as a large radiating sheet. In one of its aspects, my invention contemplates the use of a plurality of radiating elements so connected by transmission lines that impedance matching between sets of elements and the immediate feed lines is achieved and overall connection between high resistance radiators and a low resistance feed line is achieved without the use of impedance elements which tend to restrict the band width of an antenna.

2

The features of my invention which I believe to be novel are set forth with particularity in the appended claims. My invention itself, however, both as to its organization and method of operation, together with further objects and advantages thereof may best be understood by reference to the following description taken in connection with the accompanying drawings in which Fig. 1 illustrates diagrammatically a wide band antenna suitably embodying my invention; Fig. 2 illustrates certain characteristics of a conventional V-antenna; Figs. 3-6 are curves illustrating certain operational characteristics of the antenna of Fig. 1; and Fig. 7 is a diagrammatic illustration of a modification of the antenna of Fig. 1.

In Fig. 1 there is illustrated an antenna comprising four vertically spaced arrays of V-elements. Each of the arrays comprises two tubular radiators formed of a suitable conductive material having their adjacent ends relatively closely spaced and angularly related, the upper array comprising the radiators 1, 2. Disposed vertically below the radiators 1, 2 are the radiators 3, 4 which are coplanar and coextensive, respectively, with the radiators 1, 2. Third and fourth pairs of radiators 5, 6 and 7, 8 are similarly located below the radiators 1, 2 and are substantially coplanar and coextensive therewith. The radiators 3, 4 are spaced equal distances, respectively, from the radiators 1, 5 and 2, 6. Similarly, the radiators 5, 6 are spaced equal distances, respectively, from the radiators 3, 7 and 4, 8. Each of the radiators 1-8 is of uniform dimensions throughout its length and this length is determined by the frequency at which the antenna is to operate.

In accordance with my invention, I provide means for supplying current to the radiating elements so that the excitation of all the elements is in phase and each of the sets of elements 1, 3, 5, 7 and 2, 4, 6, 8, respectively, operates effectively as a sheet of high frequency current. This means comprises an open wire transmission line 45 comprising conductors 9, 10 which are connected respectively to the ends of radiators 1, 3 and 2, 4. Similarly, the adjacent ends of radiators 5, 7 and 6, 8 are connected respectively to the ends of conductors 11, 12 which comprise a second open wire transmission line. Connected to the mid points of the lines 9, 10 are the upper ends, respectively, of a pair of inner conductors 13, 14 of a pair of concentric transmission lines having tubular outer conductors 15, 16. The lower ends 55 of the inner conductors 13, 14 are similarly connected, respectively, to the mid points of the con-

ductors 11, 12. Inner conductors 13, 14, in turn, are connected at their mid points to a respective one of the conductors of an input transmission line 17. The transmission line 17 may supply high frequency currents to be radiated to the respective elements from any suitable source, such as the transmitter 18.

Preferably, the impedances of the lines 9, 10 and 11, 12 are matched respectively to the impedance of the radiating elements connected therewith. Thus, for example, the radiators 1, 2 may have an impedance of 260 ohms. If so, the open wire transmission line 9, 10 should have a surge impedance equal to 260 ohms. The upper and lower sections of the transmission line 9, 10 are in parallel at their mid points. Hence, the line 9, 10 may be connected to a coaxial transmission line arrangement having a surge impedance which is one-half the surge impedance of the line 9, 10, i. e., 130 ohms. In a similar manner, since the line 17 is connected to the mid points of the coaxial lines 13, 15 and 14, 16, the impedance at this mid point is equal to one-half the surge impedance of each of the coaxial line arrangements. Thus, the conductors of the transmission line 17 may be connected to a standard 65-ohm line, utilizing some conventional form of line balance converter at that point.

In Fig. 2, I have illustrated the terminal impedance characteristics of a one-layer V-antenna, for example, the antenna comprising the radiators 1, 2. The resistance curve 19 has a gradual increase across the band of operation. The reactance curve 20 has a positive slope and varies rapidly as the frequency is varied from a mid frequency. At the mid frequency at which the reactance is zero, the radiating elements 1, 2 are of course approximately one-quarter wave in length.

The input impedance characteristic of the antenna structure of Fig. 1 is illustrated in Fig. 3. In contrast with the characteristic of a single V-antenna, the resistance characteristic 21 of Fig. 3 is flatter than that of the characteristic 19 of Fig. 2. A greater change, however, is noticeable in the reactance characteristic 22, the slope of which is considerably smaller than the slope of the reactance curve 20 of a single V-antenna. In Fig. 3, the reactance curve 22 has a negative slope so that it may be compensated more easily by associated terminal transmission line units for well-known reasons.

In Fig. 4, there is illustrated the standing wave ratio of a single V-antenna and the antenna illustrated in Fig. 1. Thus, curve 23 shows how standing waves are established on the single V antenna as the frequency is varied from the resonant frequency, and curve 24 illustrates the same characteristic for the antenna of Fig. 1. Of particular interest is the change in frequency which is permitted without establishing a standing wave ratio greater than 1.1. Thus, comparison of curves 23 and 24 illustrates that the band of frequencies over which the operating frequency may be varied without exceeding a standing wave ratio of 1.1 for the antenna of Fig. 1 is more than three times as great as that over which the band of frequencies of a single V-antenna may be operated.

In Fig. 5, I have shown the horizontal radiation pattern of the antenna structure of Fig. 1. In this figure, curve 25 illustrates the field pattern at the mid band frequency of the antenna. Curve 26 illustrates the horizontal field pattern when the impressed frequency is 1.05 times the

mid band frequency, and curve 27 illustrates the horizontal field pattern when the impressed frequency is .95 times the mid band frequency.

According to one theory of operation in the antenna structure of Fig. 1, by splitting the current path of the high frequency currents to be radiated into four distinct circuits which extend in a transverse dimension over the entire length of the radiating conductors between the ends of those conductors, the radiators 1, 3, 5, 7 and 2, 4, 6, 8, respectively, as a group operate in effect as a single conductive sheet and the currents flow in phase from the inner edges of each of these sheets to the outer edges thereof. Best operation is obtained by proper adjustment of the spacing between adjacent radiators in each of the perpendicular planes so that the mutual reactive coupling or effective mutual inductance between adjacent conductors is a minimum. In this way, I have found that there is a minimum change of the reactance component of the antenna impedance and a multiplication or increase of the resistance component. Thus, my improved antenna achieves the basis for a band width improvement in any system, namely, a reduction in the relative values of reactance to resistance.

Generally speaking, the antenna structure of my invention proceeds on the theory that, when the number of conductors is doubled, the resistance of the individual conductors is approximately doubled and the reactance of the individual conductors is essentially unchanged. The manner in which this is made possible can best be understood from a study of the mutual impedance of layers of simple dipole antennas. For such structures, there is available information generally accepted as accurate and a portion of which is illustrated in the curves of Fig. 6. Information on V-antennas elements would show characteristics similar to those shown in Fig. 6. In Fig. 6, there is shown the variation of both mutual resistance and mutual reactance with the spacing between adjacent dipole antennas. The abscissa values are noted as the ratio of d/λ , where d is the distance between the respective dipole antennas and λ the wavelength. It will be noted from Fig. 6 that for a spacing of d such that $d/\lambda=.14$, the mutual reactance is zero, while the mutual resistance has a value which is substantially equal to the resistance of the single dipole. Of course, the resistances of the individual dipoles are denoted by the values given when $d/\lambda=0$. This distance $d/\lambda=.14$ may be called the critical spacing distance and it is this particular spacing which provides most desirable operation of arrays of elements. This characteristic, therefore, leads to certain improvements in coupling of feeding transmission lines to the antenna structure and results in a structure in which open wire transmission lines may be connected between adjacent arrays and concentric transmission lines having low impedance characteristics may be employed for supporting and connecting the open wire lines.

In order for the improvements described above to be most effective, it is desirable that every radiating conductor be spaced approximately the critical wavelength distance from each of the other conductors which form the antenna structure. When the spacing of each radiating element from the other radiating elements deviates much from the critical wavelength distance, the mutual reactance of that radiating element is not zero. Thus, although the final composite resistance increases as the number of radiating conductors,

the reactance also increases undesirably above a minimum value which is usually reached at the center of the frequency band. It is apparent, therefore, that, while the antenna arrangement of Fig. 1 provides marked improvement in impedance characteristics of antennas so that the antenna is extremely suitable for wide band operation, yet optimum spacing is not provided. One radiator arrangement which approaches the requirement of critical spacing between all the component radiators is that in which the radiators are arranged on the surface of a cylinder, rather than in vertical planes as shown in Fig. 1.

In the structure of Fig. 7, therefore, I have illustrated a modification of my antenna structure which both embodies the principles underlying the structure of Fig. 1 and incorporates a conductor arrangement which approaches a cylindrical configuration. The antenna structure there illustrated comprises two integral structures 28, 29. The structure 28 comprises a first pair of coplanar radiators 30, 31 and a second pair of coplanar radiators 32, 33. The radiators 30, 31 and 32, 33, respectively, are each arranged in the same vertical plane and the sets of radiators 34, 35 and 36, 37 are similarly each supported in the same vertical plane. The radiators 30, 34 are arranged in the same horizontal plane and have their adjacent ends so spaced that they form, in effect, a single V-antenna. Similarly, the pair of radiators 31, 35 is arranged in the same horizontal plane. Likewise, the radiators 32, 36 and the radiators 33, 37 are arranged respectively, in the same horizontal plane and each set of radiators constitutes a single V-antenna. Thus, the sets of elements 30-33 and 34-37 are each arranged along the four edges of a rectangular prism. Adjacent ends of the radiators 30, 34 are connected by means of an open wire transmission line comprising conductors 38, 39 to the upper end of an input transmission line having conductors 40, 41. Similarly, the open wire line 42, 43 connects the radiators 31, 35 to the point of connection of line 38, 39 with line 40, 41. In this structure, conductors 38, 39, 42, 43 connect diagonally opposite sets of the radiators. In structure, therefore, each of the single V-antennas is connected over an open wire line with the input line 40, 41. The four open wire lines which are connected to the four V-antennas may have their surge impedance matched to equal the impedance of the antenna and at their input points these lines are connected to an input line whose surge impedance is equal to only one-quarter that of the feed lines individually. The lines 40, 41 may be the inner conductors respectively of a pair of coaxial transmission lines having outer conductors 44, 45 and may be adapted to supply high frequency currents to the radiators 30-37 from any suitable source, such as the transmitter 18 shown in Fig. 1.

In the antenna structure of Fig. 7, therefore, there are employed four equal radiators of uniform physical characteristics which are fed with currents in phase over four short transmission lines so that all the high frequency currents seem to emanate from two conductive surfaces of large diameters increasing considerably the band width characteristics of the resultant antenna.

An important feature of my invention consists in feeding a pair of input terminals of a radiating conductor system and permitting the current to flow on the conductors over a uniform and large

area from the input terminals to the end thereof. In such a construction, of course, it is essential that the effective cross sectional dimensions of the radiating conductor be large enough so that the antenna has an effectively low reactance with a consequent increase in band width.

While, in the foregoing, I have described my invention as being applied to V-antennas, it will be obvious that other types of antennas may be used. Thus, my invention is not restricted to V-antennas but may be employed with equal advantage to radiating loops, dipoles, or rhombic antennas. In such alternative arrangements, of course, appropriate consideration should be given to the separation of the component radiators so that zero mutual reactance is obtained at the center frequency of the band over which the antenna is to operate.

While I have shown and described a particular embodiment of my invention, it will of course be understood that various changes and modifications may be made without departing from the invention and I therefore aim in the appended claim to cover all such changes and modifications as fall within the true spirit and scope of my invention.

What I claim as new and desire to secure by Letters Patent of the United States is:

In an antenna for operation over a relatively wide band of frequencies, a first group of four parallel linear radiating elements lying along the edges of a rectangular prism, adjacent elements being closely spaced from each other by a distance substantially equal to .14 times wavelength at the mean operating frequency so as to approximate a continuous radiating sheet, a second identical group of radiating elements arranged at an angle with respect to said first elements, upper and lower pairs of elements in both groups lying in the same plane and having their inner ends closely spaced to form four V-radiators, each of said elements having an effective electrical length substantially equal to .25 times wavelength at said mean operating frequency, and means to energize all the elements in each group cophasally, whereby the mutual reactance between adjacent elements in each group has a minimum value and their mutual resistance has a substantial value at said mean operating frequency.

MARVEL W. SCHELDORF.
